UNITED STATES PATENT OFFICE.

THOMAS HENRY GARLAND, OF CHICAGO, ILLINOIS.

CAR-VENTILATOR.

No. 874,320.

Specification of Letters Patent.

Patented Dec. 17, 1907.

Application filed May 10, 1907. Serial No. 372,906.

To all whom it may concern:

Be it known that I, THOMAS HENRY GARLAND, a citizen of the United States, and a resident of Chicago, in the county of Cook and State of Illinois, have invented a new and Improved Car-Ventilator, of which the following is a full, clear, and exact description.

The invention relates to car ventilators such as shown and described in the Letters Patent of the United States, No. 800,438, granted to me on September 26, 1905.

The object of the present invention is to provide a new and improved car ventilator, so arranged as to insure greater efficiency in ventilation of the car and to provide for the ventilation of berths or compartments in the car that may be separated from the clear story of the car, without danger of smoke, cinders, rain, snow, etc., passing into the car by way of the ventilator.

The invention consists of novel features and parts and combinations of the same, as will be more fully described hereinafter and 25 then pointed out in the claims.

A practical embodiment of the invention is represented in the accompanying drawings forming a part of this specification, in which similar characters of reference indicate corresponding parts in all the views.

Figure 1 is a perspective view of the improvement as applied; Fig. 2 is an enlarged sectional plan view of the same on the line 2—2 of Fig. 3; Fig. 3 is a sectional side elevation of the same on the line 3—3 of Fig. 2; Fig. 4 is a transverse section of the improvement as arranged for ventilating the clear story of the car and berths separately; Fig. 5 is a sectional plan view of the same on the line 5—5 of Fig. 4, and Fig. 6 is a sectional side elevation of the same on the line 6—6 of Fig. 4.

In the car ventilator illustrated in Figs. 1, 2 and 3, the conductor A is arranged transversely on the top of the roof B of the car, and the inner end of the said conductor A extends into an opening in the window board C, to allow of ventilating the clear story D of the car. The conductor A is provided with 50 a plurality of transverse passages A', A², A³, opening at their inner ends a distance from the inner end of the conductor A and terminating at their outer ends at or near the side of the car, as plainly indicated in Fig. 2. 55 Into the passages A', A³ extend the con-

tracted discharge ends E², E³ of cowls E, E', having their flaring entrance ends E⁴, E⁵ pointing in opposite directions, that is, between the front and rear of the car.

By the arrangement described, the passages A' and A³ are dominated by the cowls E and E', while the center passage A² is an auxiliary or supplementary passage in which a suction is produced by the discharge of the air from the cowl passages A', A², as herein-after more fully described. The center passage, A² provides a clear opening or duct from the inner end of the conductor A to the outer terminal thereof, so that a large amount of impure air in the car can be drawn out and discharged by way of the said center passage A² to the outside of the car.

The action of the ventilator when the car is in motion is as follows: When the car travels in the direction of the arrow a', the current of air caused by the forward movement of the car enters the flaring end of the cowl E at E⁴ and passes through the outlet E² into the passage A' of the conductor A. The action of this current passing through the cowl E and the passage A' produces a partial vacuum at the inner end of the conductor A, which causes the foul air in the car to enter the conductor A and be drawn out through the passage A'. When the current of air from the cowl E and the air from the conductor A through the passage A' is discharged at the outer end of the passage A' of the conductor A, it comes in contact with the current of air that is passing along the side of the car, caused by the forward motion of the car, and by this outside current of air the air from the passage A' is made to bend around over and passes the outer end of the auxiliary passage A². By this action a partial vacuum is produced at the outer end of the auxiliary passage A². This partial vacuum must be filled by foul air from the car which passes out through the auxiliary passage A² of the conductor A. The car is thus 100 ventilated by the suction caused at the inner end of the cowl passage A' and at the outer end of the auxiliary passage A². There is also a suction produced at the outer end of the cowl passage A³ when the car travels in 105 the direction of the arrow a', caused by the same action of the air from the passages A' and A² bending over the outer end of the passage A³. When the car travels in the opposite direction the action is the same; that is, 110

the air entering the cowl E' at E' produces a suction at the inner end of the passage A³ and at the outer ends of the passages A² and A'. The ventilation of the car is regulated by opening and closing the usual deck window F in front of the window-board C, which opens and closes the opening into the conductor A.

In the arrangement illustrated in Figs. 4, 10 5 and 6, two suction devices are employed, one superimposed upon the other, that is, a conductor G is arranged on the top of the conductor H held on the roof B of the car, and the inner end of the upper conductor G 15 is connected with the window-board C, while the inner end of the lower conductor H is connected with the discharge end I' of a duct I, and which discharge end I' extends through the roof B of the car, and the duct I extends 20 down the side of the car to a berth or other particular part in the lower portion of the car to be ventilated. The inlet end I² of the duct I is perforated, as illustrated in Fig. 4, and a damper J is arranged in the duct above 25 the perforations, to allow of opening or closing the duct whenever it is desired to ventilate the berth or to close the berth ventilator.

The conductors G and H are provided with 30 transversely extending partitions G', H', terminating at their inner ends a distance from the inner ends of the conductors G and H, so as to form separate passages, into which open the contracted inner ends K², K³ 35 and L², L³ of the sets of cowls K, K' and L, L', respectively, the said cowls having their entrance ends K⁴, K⁵ and L⁴, L⁵ arranged in the opposite directions, the same as above described relative to the cowls E, E'.

40 The action of each suction device described is the same as above referred to relative to the arrangement shown and described in Figs. 1, 2 and 3, that is, foul air can be drawn by the upper suction device from the 45 clear story of the car, and foul air can be drawn from a lower part of the car by way of the duct I and the lower suction device.

Having thus described my invention, I claim as new and desire to secure by Letters 50 Patent:

1. A ventilator comprising two cowls having their entrance ends pointing in opposite directions, and a conductor into which extend the outlet ends of the said cowls, the 55 said conductor having a plurality of passages in communication with each other at their inner ends.

2. A ventilator comprising two cowls having their entrance ends pointing in opposite 60 directions, and a conductor into which extend the outlet ends of the said cowls, the said conductor having its inner end opening into the car and the said conductor having a plurality of passages in communication with 65 each other at their inner ends.

3. A ventilator comprising two cowls having their entrance ends pointing in opposite directions, and a conductor into which extend the outlet ends of the said cowls, the 70 said conductor having a plurality of passages in communication with each other at their inner ends, the said outlet ends of the cowls leading into the outermost passages.

4. A car ventilator comprising two cowls having their entrance ends pointing in opposite 75 directions, a conductor into which extend the discharge ends of the said cowls, and a suction duct extending from a berth in the car and opening into the inner entrance end of the said conductor.

5. The combination with a car, of a ventilator having double suction devices, one for connection with the clear story of the car, the other suction device having a suction duct extending to a berth.

6. The combination with a car, of a ventilator having superimposed suction devices, each suction device comprising a pair of cowls having their entrance ends pointing in opposite directions, and a conductor into 90 which extend the outlet ends of the said cowls, one of the said conductors having its inlet end connected with the clear story of the car and a suction duct opening into the other conductor and extending through the 95 roof of the car and down the inside thereof.

7. The combination with a car, of a ventilator having superimposed suction devices, each suction device comprising a pair of cowls having their entrance ends pointing in 100 opposite directions, and a conductor into which extend the outlet ends of the said cowls, each conductor having a plurality of passages, and one of the said conductors having its inlet end connected with the clear 105 story of the car and a suction duct opening into the other conductor and extending through the roof of the car and down the inside thereof.

8. The combination with a car, of a ventilator having superimposed suction devices, each suction device comprising a pair of cowls having their entrance ends pointing in opposite directions, a conductor into which extend the outlet ends of the said cowls, one 115 of the said conductors having its inlet end connected with the clear story of the car and a suction duct opening into the other conductor and extending through the roof of the car and down the inside thereof, and a damper at the lower inlet end of the said duct.

9. A ventilator comprising a cowl having its entrance end pointing in the direction in which the car is traveling, and a conductor having a cowl passage and a supplementary 125 passage, of which the cowl passage contains the outlet of the said cowl and the supplementary passage is in the rear of the cowl passage, to cause a suction at the outer end of the supplementary passage.

10. A ventilator comprising a cowl having its entrance end pointing in the direction in which the car is traveling, and a conductor having one end connected with the inside of the car and the other end opening into the air at the side of the car, the said conductor having a cowl passage and a supplementary passage, of which the cowl passage contains the outlet of the said cowl and the supplementary passage is in the rear of the cowl

passage, to cause a suction at the outer end of the supplementary passage.

In testimony whereof I have signed my name to this specification in the presence of two subscribing witnesses.

THOMAS HENRY GARLAND.
